UNITED STATES PATENT OFFICE.

PAUL A. WAGNER, OF CARLSTADT, NEW JERSEY.

SUPPORT FOR HEDDLE-BARS.

1,142,290.

Patented June 8, 1915.

Application filed October 21, 1914. Serial No. 867,732.

To all whom it may concern:

Be it known that I, PAUL A. WAGNER, a citizen of the United States, residing at Carlstadt, in the county of Bergen and State 5 of New Jersey, have invented a certain new and useful Improvement in Supports for Heddle-Bars, of which the following is a specification.

The invention relates to the loops by 10 which the heddle bars are supported between the harness shafts, and the object of the invention is to provide a support of simple and economical construction, easily applied and adjusted upon the shaft, and which will 15 engage the heddle bar reliably and hold it adjustably by a strong frictional grasp against endwise displacement.

Another important object is to provide means for such grasp whereby any tendency 20 of the support to twist on the shaft or bar is avoided.

The invention consists in certain novel details by which the above objects are attained, to be hereinafter described and claimed.

25 The accompanying drawings form a part of this specification and show two approved forms of the invention.

Figure 1 is an elevation showing the preferred form of the support in service. Fig. 30 2 is an elevation on a larger scale showing one face of the same support engaged with a shaft and bar. Fig. 3 is a corresponding view of the opposite face. Fig. 4 is a vertical section taken on the line 4—4 in Fig. 3, showing the support in side view. Fig. 5 is a vertical section on the line 5—5 in Fig. 3. Fig. 6 is a horizontal section taken on the line 6—6 in Fig. 2. Fig. 7 is an elevation corresponding to Fig. 1 but showing a modified support. Fig. 8 is an elevation of the modified form with a portion of its shaft and bar. Fig. 9 is a vertical section taken on the line 9—9 in the preceding figure and showing the support in side view.

45 Similar letters of reference indicate like parts in all the figures.

Referring to Figs. 1 to 6 inclusive, A A are the shafts forming part of the frame and supplied with the usual harness, not shown, 50 B B are the heddle bars and C C the leashes or heddles, all of which may be of any approved forms, D D are the heddle bar supports, arranged in pairs on the upper and lower shafts, each pair supporting a heddle 55 bar B.

Each support is the counterpart of the other and a description of one will suffice. It comprises a strip or length of resilient material preferably spring metal bent to form the body portion D inclosing the shaft 60 A, and its ends continued in the form of straight parallel arms D¹ D¹ adapted to be forced together in opposition to the spring of the body portion which tends to separate them, as indicated by the dotted lines in 65 Fig. 5.

Each arm is slotted on lines parallel with its edges and the metal forced out of the plane of the arm to form a single intermediate loop D² on one face and two outer loops 70 D³ D³ on the other face, and the loops D² D³ of both arms are on corresponding faces and so shaped that when the arms are forced together in clamping the body portion D upon the shaft A the two loops D² and the 75 four loops D³ match or nest together to provide a composite opening d in which the heddle bar is received. The bar is thus inclosed and frictionally grasped and is held strongly enough to prevent unintentional 80 endwise movement but may be shifted in the supports as desired in grouping the heddles by exerting sufficient force to overcome the frictional resistance.

D⁴ D⁴ are spurs on the inner faces of the 85 body portion D adapted to be forced into the wood of the shafts to maintain the support in position when closed thereon.

The heddles C C are looped upon the heddle bars B B in the ordinary manner and 90 may be spaced, grouped and located as usual.

By reason of the single loop D² on one face of each arm D¹ lying between the loops D³ D³ on the other face, and the nesting of 95 the loops of one arm with those of the other, the arms are securely interlocked by the introduction of the bar B, and the torsional strains of the arms tending to bend or distort the bar or twist the body portion D 100 upon the shaft are eliminated, thus permitting the bar to lie straight and in parallelism with the shafts and companion bar.

In the support shown in Figs. 7, 8 and 9 the body portion D⁰ is similar to the form 105 above described but the arms D⁵ D⁵ are given a quarter turn, as at D⁷, to extend parallel with each other and face to face transversely of the shaft. The arm D⁵ is straight beyond the twist D⁷, and the arm D⁶ is 110

folded upon it to form a loop or bight D^8 inclosing the end of the arm D^5 thus providing three thicknesses of the metal. All are pierced as at d^1 to receive the bar B^1 which is thus held and subjected to the frictional tension supplied by the tendency of the arms to separate angularly.

By engaging the bar at two separated points in the folded or double arm D^8 and 10 also at a point between in the straight or single arm D^5 the torsional tendency of the arms to spring or distort the bar is avoided in the same manner as by the engagement of the single loops D^2 between the flanking 15 loops D^3 D^4 in the form first described.

Any suitable material may be employed for the supports and the proportions may be varied to suit conditions of service. The bar may be cylindrical or of other cross-section 20 with the loops correspondingly shaped to receive it and the support may be formed of wire bent to inclose the shaft and form the desired loops. Both forms of the device as illustrated may be easily and cheaply 25 manufactured, applied and adjusted.

I claim:—

1. In a heddle bar support, a length of 30 resilient material bent to form an open body portion adapted to inclose a harness shaft, and having arms shaped to lie together and receive and be interlocked by the introduction of a heddle bar therethrough, said arms arranged to grasp said bar at two separated outer points thereon and at an intermediate 35 point and hold said bar frictionally against longitudinal movement, without transmit-

ting torsional strains of such arms to said shaft and bar.

2. In a heddle bar support, a length of 40 spring metal bent to form an open body portion adapted to inclose a harness shaft, and having arms arranged to lie face to face, each of said arms having a single loop on one face intermediate a pair of loops on the opposite face, the loops of one arm constructed to nest with the loops of the other arm and receive a heddle bar thrust through such nested loops, and hold said bar frictionally in opposition to a longitudinal movement relatively to such support. 45

3. In a heddle bar support, a strip of 50 spring metal bent to form an open body portion adapted to inclose a harness shaft, spurs on said body portion adapted to engage such shaft, said body portion having arms formed integrally therewith and adapted to lie face to face, each of said arms having two slits parallel with its edges, with the metal between such slits bent out on one face to form a loop, and the metal on each 55 side of such loop bent out on the opposite face to form two loops, the loops of one arm adapted to nest with those of the other and receive a heddle bar thrust through such nested loops. 60

In testimony that I claim the invention above set forth I affix my signature, in presence of two witnesses.

PAUL A. WAGNER.
